UNITED STATES PATENT OFFICE.

ISAAC L. OSBORNE, OF REDMOND, OREGON.

HAY-RACK.

1,124,793.

Specification of Letters Patent.

Patented Jan. 12, 1915.

Application filed June 6, 1914. Serial No. 843,444.

To all whom it may concern:

Be it known that I, ISAAC L. OSBORNE, a citizen of the United States, and a resident of Redmond, in the county of Crook and State of Oregon, have invented a new and useful Improvement in Hay-Racks, of which the following is a specification.

My invention is an improvement in hay racks, and has for its object to provide a combination rack of the character specified, capable of being expanded into rack form or contracted into compact form for handling or storing, and wherein the rack may be converted into a rack for supporting hay, straw, or the like, or into a crate or cage for conveying live stock, as for instance, hogs, sheep, calves, or the like.

In the drawings:—Figure 1 is a side view of the improved rack, Fig. 2 is a top plan view, Fig. 3 is an end view with the rack in use as a rack, Fig. 4 is a transverse vertical section, Fig. 5 is front view of the front rail, Fig. 6 is an end view with the rack arranged as a crate or cage, Fig. 7 is an enlarged partial side view of one of the side frames, and Fig. 8 is a front view of a modified form of end gate.

The present embodiment of the invention comprises a base, consisting of upper and lower bed plates 1 and 2 of suitable length, and the bed plates connect front and rear frames. The front frame is composed of side plates 3, connected by pairs of front and rear cross bars 4 and 4^a, the bed plates 1 and 2 being arranged above and below the cross bars 4 and 4^a, and being secured to the said cross bars as shown, intermediate the side plates 3. The members of each pair of cross bars 4 and 4^a are spaced apart from each other as shown, and the adjacent members of the pairs are connected at the side plates 3, by longitudinally extending plates 5.

The rear frame consists of side plates 6, front and rear pairs of cross bars 7 and 7^a and a central cross bar 8, the cross bars connecting the side plates. The bed plates 1 and 2 are secured to the cross bars 7, 7^a and 8, as shown in Fig. 2. Flooring plates 9 are laid on the cross bar 8, and on the adjacent members of the pairs of cross bars 7 and 7^a between the upper bed plate 1 and the side plates 9. The members of each pair of cross bars 7 and 7^a are spaced apart in the same manner as the members of the pairs 4 and 4^a of the front frame.

The side plates 3 of the front frame and the side plates 6 of the rear frame are provided with bearing clips 10 on their outer faces, each of the plates having two clips, 60 and the front cross bar of the pair 4 is also provided with a pair of clips 10^a on its outer face similar to the clips 10 of the side plates 3 and 6. Side frames are also provided, each of the said frames consisting of four uprights 11, and four standards 12, and the lower ends of the standards 12 are adapted to be received in the clips 10 of the side plates 3 and 6, when the side frames of the rack are in vertical position to form a 70 crate or cage.

The standards 12 are arranged with their wide dimensions in the plane of the side, that is, with their wide dimensions in the same plane, while the uprights are arranged with their wide dimensions parallel. A standard 12 is provided for each clip 10, and an upright 11 is arranged adjacent to each standard on the outer side thereof. The upper ends of the uprights 11 are beveled as indicated at 13 in Figs. 3 and 4, and longitudinally extending plates 14 are arranged on the beveled ends and are secured to the uprights in any suitable manner.

Bolts 15 are passed through the ends of 85 the uprights at the beveled surfaces and through the plates 14, and each bolt is provided with a nut 16 at its upper end. When the sides are arranged to be used as a rack as shown in Figs. 3 and 4, rails 17 and 18 90 are arranged transversely of the base frame at the front and rear ends for connecting the outer side of the side frames, and each of the rails 17 and 18 is provided with an opening at each end for receiving the end 95 of the adjacent bolt 15, and a reinforcing plate 19 is arranged transversely of each end of each rail on the upper face thereof, each plate 19 having an opening registering with the opening of the rail, and the reinforcing plates are secured to the rails in any 100 suitable or desired manner.

The front rail 17 differs slightly from the rear rail 18 in that on each side of its center and at its front edge notches 20 are provided, and a substantially U-shaped bracket comprising a body 21 and arms 22 is connected with the rail. The body 21 of the bracket has its wide dimension vertical and is spaced in front of the front edge of the 110 rail as shown in Fig. 5. The arms 22 of the bracket are secured to the upper face of the

rail, the inner edges of the arms being at the outer edges of the notches 20.

The rear end of each arm is turned downwardly to fit against the rear edge of the rail as indicated at 23, and the bracket is designed to hold a ladder. The ladder consists of stiles connected by rungs 25, and the lower ends of the stiles are adapted to engage the clips 10^a on the front cross bar 10 of the pair 4. The stiles also pass through the notches 20 and the body 21 of the bracket forms a guide and a guard for the ladder.

The side frames are completed by a longitudinally extending plate 26, which connects all of the uprights and all of the standards and by other plates 27 and 28, respectively. It will be noted from an inspection of Fig. 1 that the plates 14 and 26 extend the full length of the side frames, and that the uprights are arranged to correspond with the arrangement of the pairs of cross bars 4-4^a, 7 and 7^a. The plates 27 connect the two uprights and the two standards, at the front of the side, while the plates 28 connect the two uprights and the two standards at the rear of the frame.

That portion of the side frames below the plate 26 and between the adjacent ends of the side plates 3 and 6 is open, and each may be closed by a door 29. Each of the doors is connected to the plate 26 by hinges 30, and the ends of the plates which form the gate are adapted to fit against the outer edges of the uprights 11 between the plates 26 and 28 and 26 and 27.

Each of the longitudinal plates of each gate is notched or rabbeted at its ends and at its under edge as indicated at 31, and each of the inner ends of the plates 27 and 28 are similarly notched or rabbeted as indicated at 32. The rabbeted portion of the plates 27 and 28 leaves sufficient of each plate extending inwardly beyond the adjacent upright to fill the adjacent notch of the adjacent gate plate when the gate is closed as shown more particularly in Fig. 7.

When the side frames are to be used, as a crate or cage, the lower ends of the standards 12 are engaged with the clips 10, while when the side frames are connected with the base to form a rack as shown in Figs. 3 and 4, the lower ends of the uprights 11 are inserted between the members of the pairs of cross bars 4-4^a, 7-7^a. It will be noted that neither the floor plates 5 or 9 extend beyond the inner cross bar, and the ends of the uprights are passed between the members of the pairs and between the bed plates.

The lower end of each upright is cut away on its outer face as indicated at 33, and the inner corner of the lower end is beveled as shown at 34. When the uprights of the opposite sides are engaged between the cross bars and between the bed plates,

the beveled ends 34 will abut and fit against each other. The cutting away 33 of the outer edge is for the purpose of permitting the lower ends to fit between the bed plates.

The arrangement of the gates 29 is such that they may swing inward at their lower ends but cannot swing outward, the ends of the longitudinal plates of the gate engaging the uprights 11 to prevent such outward swinging movement, and this is true whether the sides are arranged vertical as in Fig. 6 or in inclined position as in Figs. 3 and 4.

Front and rear end gates are provided for closing the rack when arranged as a crate or cage, and the said gates are similar. Each gate consists of a pair of vertical bars 35, and three longitudinally extending plates 36, the said plates connecting the vertical bars and being arranged in spaced relation. The ends of the plates 36 are reduced at 37 and extend beyond the cross bars 35 and beyond the uprights 11 of the said frames when the side frames are in vertical position as shown in Fig. 6.

Bolts 38 are passed through openings in the uprights at the front and rear ends, and in the intermediate uprights, and each bolt is engaged by a nut 39. The upper and lower bars 36 of each gate are provided with openings adapted to receive the bolts of the uprights at the ends of the side frames when the gates are in place and the nuts 39 will hold the gates in position, and the gates will assist in bracing the side frames. A pair of intermediate gates or partitions is also provided for connection with the intermediate uprights, each of the said partitions comprising vertical laterally spaced bars 40, connected by an upper cross plate 41, and a lower cross plate 42. The upper cross bar 41 has its ends extended beyond the vertical bars fitting between the plates 14 and 26 of the side frame, and the bolts 38 of the intermediate uprights 11 are passed through openings in the reduced ends and are engaged by the nuts in the usual manner to hold the gates in place. It will be noted that each of the plates 36 is bolted to an upright in Fig. 1.

From an inspection of Figs. 1 and 2, it will be noted that when the device is used as a rack in the form shown in Figs. 3 and 4, the front wheels may be turned as in the usual manner without striking any part of the rack. The gates 29 and the spacing between the adjacent side plates 3 and 6 will permit this movement. This is a great advantage, since it permits a load of hay or straw to be handled much easier than where the front wheels cannot turn.

In use, when it is desired to set up the rack as a rack the bottom or base frame is seated on the wagon on the bolsters in the usual manner. The side frames are now

arranged as shown in Figs. 3 and 4, and the upper free ends of the side frames are connected by the front and rear rails 17 and 18. The ladder is now placed, and the rack 5 is ready for use. When loaded the gates are supported by their engagement with the uprights, so that the load cannot fall out through the gates. When it is desired to transform the rack into a crate or cage the 10 rails 17 and 18 are removed and laid aside.

Each side frame is arranged as shown in Fig. 1, the lower ends of the standards being engaged with the clips 10. The front and rear end gates are then placed and secured 15 to the end uprights of the said frames by the bolts 38, and the nuts 39. Before placing the intermediate gates or partitions, floor boards not shown are dropped into place on each side of the upper bed plate 1 between 20 the adjacent ends of the floor boards 5 and 9. The intermediate gates or partitions are then placed and secured in place to the uprights, and the said partitions or gates hold the floor boards above mentioned 25 in place.

It will be noted from an inspection of Fig. 2 that each of the side frames 3 and 6 is grooved or mortised as indicated at 46 at the space between the members of each 30 pair of cross plates 4-4^a, 7 and 7^a, for receiving the uprights.

The improved rack is easily adjusted to either form, and when it is desired to store the same the parts may be folded into small 35 space. When converted into a crate or cage, there are three compartments, so that the animals may be separated into small lots, thus preventing the liability of damage from each other. In addition the farmer has two 40 complete implements in a single form.

Each end gate shown in Fig. 8 comprises cross plates 47 and vertical bars 48 at its ends, the bars being secured to the plates in any suitable manner. A V-shaped brace 45 is also connected with the gate, the said brace consisting of two portions 49, converging at their upper ends and secured to the plates 47. The portions or plates 49 are beveled at their ends to fit closely against 50 each other at the bottom of the gate and to fit closely against the bars 48 at the top of the gate.

It will be evident that the improved rack may be left permanently in either condition, 55 either as a rack or as a crate if desired. It is also evident that in either form certain elements might be omitted. For instance in a rack the end gates, the transverse gates, and the floor boards would not be needed, 60 while as a crate the front and rear rails 17 and 18 and the ladder would not be needed.

I claim:—

1. A rack comprising a base consisting of front and rear frames spaced apart from 65 each other at their adjacent ends, each

frame having at each end a transversely extending vertical slot, upper and lower bed plates arranged longitudinally of the base and connecting the frames at the center of the base, holding clips at each side of each 70 of the frames, side frames each having standards for engaging the clips at the adjacent side of the base for permitting the side frames to be connected with the base in approximate parallelism and approximately 75 vertical to the base, and having uprights fitting the transverse slots between the bed plates and resting on the base at the sides thereof to permit the side frames to be connected with the base in inclined position diverging from 80 the base toward their upper ends, front and rear rails for connecting the upper edges of the side frames at their ends when in inclined position, and a series of gates for connecting the side frames when 85 in vertical position, each side frame having a hinged gate at the space between the front and rear frames of the base, said gate being hinged at its upper side edge to swing inwardly and upwardly, means in connection 90 with each gate and the side frame for limiting the outward swinging movement of the gate to a position in the plane of the adjacent side frame, and a ladder detachably connected with the front end of the base, 95 the front side rail having means for embracing the ladder.

2. A rack comprising a base consisting of front and rear frames spaced apart from each other at their adjacent ends, each frame 100 having at each end a transversely extending vertical slot, upper and lower bed plates arranged longitudinally of the base and connecting the frames at the center of the base, holding clips at each side of each of the 105 frames, side frames each having standards for engaging the clips at the adjacent side of the base for permitting the side frames to be connected with the base in approximate parallelism and approximately vertical 110 to the base, and having uprights fitting the transverse slots between the bed plates and resting on the base at the sides thereof to permit the side frames to be connected with the base in inclined position diverging from 115 the base toward their upper ends, front and rear rails for connecting the upper edges of the side frames at their ends when in inclined position, and a series of gates for connecting the side frames when in vertical 120 position, each side frame having a hinged gate at the space between the front and rear frames of the base, said gate being hinged at its upper side edge to swing inwardly and upwardly, and means in connection with 125 each gate and the side frame for limiting the outward swinging movement of the gate to a position in the plane of the adjacent side frame.

3. A hay rack comprising a base consist- 130

ing of front and rear frames spaced apart from each other at their adjacent ends, each frame having at each end a transversely extending vertical slot, upper and lower bed 5 plates arranged longitudinally of the base and connecting the frames at the center of the base, holding clips at each side of each of the frames, side frames each having standards for engaging the clips at the adjacent 10 side of the base for permitting the side frames to be connected with the base in approximate parallelism and approximately vertical to the base and having uprights fitting the transverse slots between the bed plates and resting on the base at the sides thereof to permit the side frames to be connected with the base in inclined position diverging from the base toward their upper ends, front and rear rails for connecting the 15 upper edges of the said frames at their ends when in inclined position, and a series of gates for connecting the side frames when in vertical position, each side frame having

a hinged gate at the space between the front and rear frames of the base, said gate being hinged at its upper side edge to swing inwardly and upwardly. 25

4. A hay rack comprising a base consisting of front and rear frames spaced apart from each other, upper and lower bed plates 30 extending longitudinally of the base above and below the frames and secured to the frames at the center of the base, side frames, each of the said side frames and the base having interengaging means for permitting 35 the side frames to be connected to the base in approximately vertical position or in inclined position, each side frame having a gate at the space between the front and rear frames, and hinged at its upper side to 40 swing inward and upward for the purpose specified.

ISAAC L. OSBORNE.
